143,165

DESIGN FOR A BRASSIÈRE OR SIMILAR GARMENT

Raymond J. Redares, Los Angeles, Calif.

Application January 22, 1945, Serial No. 117,546

Term of patent 14 years

(Cl. D20—4)

To all whom it may concern:

Be it known that I, Raymond J. Redares, a citizen of the United States and a resident of the city of Los Angeles, in the county of Los Angeles and State of California, have invented a new, original, and ornamental Design for a Brassière or Similar Garment, of which the following is a specification, reference being had to the accompanying drawing, forming part thereof, in which:

The figure on the drawing is a plan view of a brassière showing my new design.

The inside of the brassière follows substantially the same lines as the side shown.

I claim:

The ornamental design for a brassière or similar garment, substantially as shown and described.

RAYMOND J. REDARES.
